UNITED STATES PATENT OFFICE

2,037,956

MANIPULATOR

Joseph A. Wolle, Collingswood, N. J.

Application August 18, 1934, Serial No. 740,415

10 Claims. (Cl. 128—48)

My invention relates to manipulators, that is to say, to improved apparatus for performing manipulations upon the body, wherever such manipulations are desirable, as for example upon the face and neck portions thereof.

Heretofore it has been well known that wrinkles, lines, and flabby skin may be largely eliminated by proper manipulation of the parts where such wrinkles, lines, and flabbiness occur.

10 It has been found that the most effective form of manipulation is that in which a succession of light blows or pats are used, combined with a suitable amount of friction or rubbing.

Such manipulations, when performed by the 15 hands of the operator, are tiring and cannot be continued for a sufficient length of time to obtain the desired results.

The principal object, therefore, of my present invention is to provide a simple and efficient 20 manipulator of the motor driven type, which may be conveniently employed for manipulating various portions of the body, and by means of which a peculiar patting and lifting action will be combined with a frictional or rubbing action.

25 A further object of my invention is to provide a device of the character aforesaid, by means of which the manipulations may be conveniently applied to each of the various parts, and in the proper direction for the most effective action.

30 A further object of my invention is to provide a device of the character aforesaid, in which the manipulation member may, if desired, be covered by a removable apron, so that, for sanitary reasons, a new apron may be readily substituted for one which has been used.

35 A further object of my invention is to provide a device of the character aforesaid, which is constructed and arranged for the utmost facility and convenience in its use.

40 The nature and characteristic features of my invention will be more readily understood from the following description, taken in connection with the accompanying drawings forming part hereof, in which:

45 Figure 1 is a side elevation of a manipulator embodying the main features of my present invention;

Fig. 2 is a top or plan view thereof, partly broken away;

50 Fig. 3 is a fragmentary sectional view illustrating certain details of the mechanism;

Fig. 4 is a side elevational view of a modified form of the manipulator;

Fig. 5 is a front elevation thereof; and

55 Fig. 6 is a fragmentary sectional view illus-

trating the internal construction of the manipulator shown in Figs. 4 and 5.

It will, of course, be understood that the description and drawings herein contained are illustrative merely, and that various modifications 5 and changes may be made in the structure disclosed without departing from the spirit of the invention.

Referring now more particularly to Figs. 1 to 3 of the drawings, in the particular embodiment of my invention therein shown, 10 is an electric motor of any preferred type. Mounted on one end of said motor is a handle member 11, preferably provided with an internal switch (not shown), which may be operated by the button 15 12, for controlling the starting and stopping of the motor. Current is supplied to the motor through the cable 13.

On the other end of the motor 10 there is mounted a bracket member 14, through which 20 the motor shaft 15 extends. The motor shaft 15 is provided with a worm 16, which meshes with and drives a worm wheel 17. The worm wheel 17 is mounted on and secured to a transversely extending shaft 18, which is journaled in 25 an upwardly extending portion 19 of the bracket member 14.

The respective ends of the transverse shaft 18 extend beyond the sides of the upwardly extending portion 19 of the bracket member 14, and 30 on each end of said shaft there is mounted a crank disk 20. Each crank disk 20 is provided with a crank pin 21, upon which one end of a connecting rod 22 is journaled. The other end of said connecting rod 22 is connected by means 35 of a pin 23 to a bracket member 24 which is secured to a portion of a leaf spring 25. The leaf spring 25 is of peculiar conformation, the ends thereof being secured between the bracket member 14 and the end face of the motor 10. 40

The leaf spring 25 extends upwardly at one end, as at 26, from the place where it is clamped between the bracket member 14 and the motor 10, then being bent over and extending forwardly, as at 27, to a rounded apex 28, from which it extends downwardly and rearwardly, as at 29, thence extending horizontally as at 30, thence being provided with a series of convolutions as at 31, and finally extending upwardly at the 45 other end, as at 32, to the place where said end is clamped between the bracket member 14 and the end face of the motor 10. The bracket member 24, by means of which the connecting rods 22 are pivotally connected to the leaf spring 25, 50 55

is preferably secured to the horizontally extending portion 30 of said leaf spring.

Upon the rounded apex 28 of the leaf spring 25 there is preferably provided a pad 33, which 5 may be made of a suitable resilient material such as felt, sponge rubber, or the like.

Extending over the pad 33 is an apron 34, which 10 may be made of any suitable material such as woven fabric, leather, rubber, or the like. The apron 34 is preferably made removable, so that, for sanitary reasons, a new apron may be substituted for one which has been used.

The ends of the apron 34 are secured to the portions 27 and 29 of the leaf spring 25 by separable fasteners 35, which may be of any preferred type, such for example as the type of those commonly used on gloves.

The operation of the manipulator above described will be readily apparent. When the current is switched on, and thereby supplied to the motor 10, the motor shaft 15 will be rotated, the worm 16 carried thereby rotating the worm wheel 17, and consequently the transverse shaft 18 upon which the worm wheel is mounted.

As the transverse shaft 18 is thus rotated, the crank disks 20 will rotate in unison therewith, and through the medium of the connecting rods 22, will cause the leaf spring 25 to be actuated with a peculiar movement, so that when the pad 33 carried at the apex 28 of the spring 25 is applied to the portion of the body to be manipulated, a patting and lifting action will be imparted to said manipulating device.

In Figs. 4 to 6 of the drawings, there is shown 35 a modified form of the invention, in which the leaf spring is dispensed with, and in lieu thereof there is provided a manipulation member 36, comprising a hollow body portion 37 and a projecting lobe portion 38.

The manipulation member 36 is journaled on 40 a stationary shaft 39 which is carried by arms 40 projecting from the extending portion 19 of the bracket member 14, in which the worm wheel 17 is journaled. A coil spring 41 is positioned 45 within the hollow interior 37 of the manipulation member 36, one end of said spring 41 being connected to said manipulation member as at 42, and the other end being connected to the stationary shaft 39, as at 43. This spring 41 serves 50 to impart a return movement to the manipulation member 36, as will be hereinafter more fully set forth.

The connecting rods 22, in the present instance, are connected at their ends, by means of 55 a transverse pin 44, to one end of an apron 45 which extends around the lobe portion 38 of the manipulation member 36. The pin 44 is preferably made removable. The other end of said apron 45 is removably secured to the manipulation member 36, preferably by means of a hook 46, whereby said apron 45 may be removed 60 from said manipulation member and replaced by another apron, for sanitary purposes.

The operation of the modified form of the invention shown in Figs. 4 to 6 may now be explained. The motor 10, worm 16, and worm wheel 17, operate as in the form shown in Figs. 1 to 3 of the drawings, serving to rotate the crank disks 20, whereby a reciprocating motion is imparted to the ends of the connecting rods 22. This reciprocating motion is in turn applied to the apron 45, thus causing the manipulation member 36 to be oscillated about the axis provided by the shaft 39, and against the tension of 75 the internal coil spring 41.

It should be understood that, in the use of such devices, suitable creams are usually employed, principally for the purpose of preventing frictional abrasion of the skin.

It will be seen that, in the use of either of 5 the forms of the invention, a peculiar patting and lifting action is obtained, and when the manipulation member is applied to the skin, the desired beneficial results will be obtained without undue fatigue of the operator. 10

I claim:

1. A manipulator comprising a motor, a shaft driven by said motor, a manipulation member, an apron extending over said manipulation member, a leaf spring upon a portion of which the manipulation member is secured, said leaf spring having its ends fixedly secured, and means actuated by the motor driven shaft for oscillating said leaf spring and the manipulation member carried thereby. 20

2. A manipulator comprising a motor, a shaft driven by said motor, a manipulation member, a leaf spring upon a portion of which the manipulation member is secured, said leaf spring having its ends fixedly secured, and means actuated 25 by the motor driven shaft for oscillating said leaf spring and the manipulation member carried thereby.

3. A manipulator comprising a motor, a shaft driven by said motor, a manipulation member, a 30 removable apron extending over said manipulation member, a leaf spring having its ends fixedly secured and having an intermediate portion formed into an apex upon which the manipulation member is secured, a crank mounted on the 35 motor driven shaft, and a connecting rod extending from said crank to a portion of the leaf spring between the place where the manipulation member is secured and one of the fixed ends of said leaf spring, said leaf spring having convolutions 40 to increase its flexibility.

4. A manipulator comprising a motor, a shaft driven by said motor, a manipulation member, an apron extending over said manipulation member, a leaf spring having its ends fixedly secured 45 and having an intermediate portion upon which the manipulation member is secured, and connecting means actuated by the motor driven shaft extending to a portion of the leaf spring for oscillating said leaf spring and the manipulation member 50 carried thereby.

5. A manipulator comprising a motor, a shaft driven by said motor, a manipulation member, a leaf spring having its ends fixedly secured and having an intermediate portion upon which the 55 manipulation member is secured, and connecting means actuated by the motor driven shaft extending to a portion of the leaf spring for oscillating said leaf spring and the manipulation member carried thereby.

6. A manipulator comprising a motor, a shaft driven by said motor, a manipulation member, an apron extending over said manipulation member, a leaf spring having its ends fixedly secured and having an intermediate portion upon which the 65 manipulation member is secured, a crank mounted on the motor driven shaft, and a connecting rod extending from said crank to a portion of the leaf spring between the place where the manipulation member is secured and one of the fixed ends 70 of said leaf spring.

7. A manipulator comprising a motor, a shaft driven by said motor, a manipulation member, an apron extending over said manipulation member, a leaf spring having its ends fixedly secured and 75

having an intermediate portion formed into an apex upon which the manipulation member is secured, a crank mounted on the motor driven shaft, and a connecting rod extending from said 5 crank to a portion of the leaf spring between the place where the manipulation member is secured and one of the fixed ends of said leaf spring.

8. A manipulator comprising a motor, a shaft driven by said motor, a manipulation member, a 10 removable apron extending over said manipulation member, a leaf spring having its ends fixedly secured and having an intermediate portion formed into an apex upon which the manipulation member is secured, a crank mounted on the motor driven shaft, and a connecting rod extending from 15 said crank to a portion of the leaf spring between the place where the manipulation member is secured and one of the fixed ends of said leaf spring,

said leaf spring having convolutions to increase its flexibility.

9. A manipulator comprising a motor, a shaft driven by said motor, a manipulation member, a leaf spring mounting for said manipulation member, said leaf spring mounting having its ends fixedly secured, and means actuated by said shaft for oscillating said manipulation member. 5

10. A manipulator comprising a motor, a shaft driven by said motor, a manipulation member, a leaf spring mounting for said manipulation member, said leaf spring mounting having its ends fixedly secured, and means actuated by said shaft for oscillating said leaf spring and the manipulation member mounted thereon, said means including a connecting rod interposed between the shaft 10 and the leaf spring. 15
